Primary Examiner — Samantha Q Lawrence*Assistant Examiner* — Holly M Rodriguez(74) *Attorney, Agent, or Firm* — Leydig, Voit & Mayer Ltd.; John Augustyn(57) **CLAIM**

The ornamental design for a speaker, as shown and described.

DESCRIPTION

FIG. 1 is a front perspective view of a speaker of the present invention;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof; and,

FIG. 8 is a right side view thereof.

The broken lines shown in FIGS. 3-4 and 6-8 illustrate portions of the docking station with a speaker that form no part of the claimed design.

1 Claim, 5 Drawing Sheets
